(74) *Attorney, Agent, or Firm* — Schwegman Lundberg & Woessner, P.A.**CLAIM**

The ornamental design for a shoulder prosthesis, as shown and described.

DESCRIPTION

FIGS. 1-6 show a shoulder prosthesis in accordance with my new design, wherein:

FIG. 1 is a first perspective view thereof;

FIG. 2 is a second perspective view thereof;

FIG. 3 is a front/rear view thereof, it being understood that the front and rear views are identical;

FIG. 4 is a right side/left side view thereof, it being understood that the right side and left side views are identical;

FIG. 5 is a bottom view thereof; and,

FIG. 6 is a top view thereof.

The broken line showing of the center hole in FIG. 5 is included for the purpose of illustrating environment and forms no part of the claimed design.

1 Claim, 3 Drawing Sheets(56)
